UNITED STATES PATENT OFFICE.

STANISLAW OBOLEWICZ, OF DETROIT, MICHIGAN, ASSIGNOR TO JOSEPH NIGBOR, OF DETROIT, MICHIGAN.

COMBINED MOP AND BRUSH HANDLE.

1,325,165.

Specification of Letters Patent.

Patented Dec. 16, 1919.

Application filed June 16, 1919. Serial No. 304,537.

To all whom it may concern:

Be it known that I, STANISLAW OBOLEWICZ, a citizen of Poland, residing at Detroit, in the county of Wayne and State of Michigan, (whose post-office address is care of Patent Experimental Co., No. 2236 Michigan street, Detroit, Michigan,) have invented certain new and useful Improvements in Combined Mop and Brush Handles, of which the following is a specification.

The primary object of the present invention is to provide an improved construction of brush and mop holders especially designed for use in connection with cleaning of motor vehicles in which a cloth in the form of a small mop may be easily and quickly secured in position upon the handle head for purposes of dusting or cleaning an automobile.

20 A further object of the invention is to provide a combined brush and mop handle that is designed either to hold a brush or a mop and wherein the brush or mop engaging jaws are located at one side of the handle so that the brush or mop carried by the jaws will be in an advantageous position relative to the handle when the device is used for cleaning the upper sides and top of a motor vehicle.

30 A further object of the invention is to provide a combined mop and brush handle in which the clamping jaws of the handle head are operated by a flexible connection extending to the rear end of the handle whereby it is possible to cause the jaws to grasp a brush or a wet mop or cloth by manipulating the jaws from the inner end of the handle without the operator using his hands to apply the same.

40 With the above and other objects in view, the invention consists in the novel form, combination and arrangement of parts herein fully described, shown in the accompanying drawing then claimed.

45 In the drawings forming a part of this application, wherein like reference characters indicate similar parts throughout the several views,

Figure 1 is a side elevational view of the combined brush and mop holder constructed in accordance with the present invention, the handle portion thereof being shown in longitudinal section,

Fig. 2 is a bottom plan view thereof,
55. Fig. 3 is a cross sectional view taken on

line III—III of Fig. 1 showing the flexible connection between the movable clamping jaw and the operating lever,

Fig. 4 is a detail perspective view of the fixed jaw and supporting thimble removed 60 from the handle and detached from its cooperating jaw and

Fig. 5 is a cross sectional view taken on line V—V of Fig. 1 showing the device for holding the operating lever in locked position.

Describing the invention more in detail, the reference numeral 6 denotes the handle portion of the device which is of hollow or tubular construction as illustrated in Figs. 70 1 and 3 while coöperating jaws 7 and 8 are carried by one end thereof.

The jaw 7 is shown in detail in Fig. 4 detached from the handle 6 and comprising a relatively long tubular portion 9 that is 75 adapted to receive the handle 6 for rigidly mounting the same. As illustrated in Fig. 4, the jaw 7 is formed of a single piece of material embodying the handle engaging portion 9 with the forward end thereof bent 80 substantially at right angles thereto providing a face portion 10 cut away intermediate the ends thereof to provide side bars 11, the outer end 12 of the front face having the engaging jaw 13 bent outwardly substantially at right angles thereto and having the working edge thereof serrated to provide teeth 14.

The jaw 8 is clearly shown in Figs. 1 and 2 and includes a face section 15 carrying 90 side bars 16 that are pivoted between the side bars 11 of the jaw 7 upon pins 17 extending through registering openings 18. A gripping jaw 19 is carried by the outer end of the front wall 15 of said jaw 8 and 95 is provided upon the edge thereof with teeth 20 coöperating with the teeth 14 upon the jaw 7 in a manner to interlock when moved toward each other. A rearwardly and angularly extending arm 21 is carried by the inner end of the jaw 8 for purposes presently to appear. The pivot pin 17 is surrounded by a coil spring 22, the end 23 of which extends toward the outer end of one of the legs 11 and is secured about the same as shown 105 in Fig. 3 while the opposite end 24 of said spring engages the inner face of the jaw wall 15 so that there is a normal tendency for the jaws to remain in their open position as shown by dotted lines in Fig. 1.

An operating lever is provided for closing the jaws 7 and 8 and comprises in detail, a band 25 secured around the handle 6 at the end opposite the jaws 7 and 8 and has hinge-
5 edly secured thereto as at 26, a lever 27. A pair of rollers 28 are journaled interiorly of the tubular handle 6 and over which the operating cord 29 is adapted to pass, the forward end of the cord in leaving the front
10 roller 28 passes through registering openings 30 in the jaw sleeve 7 and handle 6 for engagement with the rear end 31 of the jaw arm 21 while the opposite end of the cord 29 passes through a slotted opening 32 in the
15 upper wall of the handle 6 with the terminal end thereof passed through an opening from the upper side of said lever and prevented from being withdrawn therefrom as by knotting the same as indicated at 33 or otherwise
20 retaining the same in position.

With the device in the dotted line position shown in Fig. 1, the cloth or mop head A is positioned between the engaging flanges 13 and 19 of the jaws 7 and 8 and by swing-
25 ing the lever 27 from the dotted line position to the full line position shown, the connecting cord 29 between said lever and jaw 8 will cause said jaw to move toward the jaw 7 and clamp the mop A therebetween.
30 When so arranged, and it being desired to hold the mop permanently positioned, the pin 34 movable through a slot 35 in the lever 27 has the lower angle end 36 thereof received in the notch 37 provided on the inner face of the ring 38 that is secured to the
35 handle 6 as shown in Figs. 1 and 5 so that when the pin engages said notch ring, the

lever 27 is locked in its closed position adjacent the handle and the mop permanently retained between the jaws 7 and 8. If it be 40 desired to replace the mop or cloth with a new one or to insert a brush head between the jaws in lieu of the mop, the pin 34 is moved in the slot 35 to release the hooked end 36 from the notched ring 38 at which 45 time the lever 27 may be swung upon its pivot 26 to permit the spring 22 to open the jaws 7 and 8.

While I have herein shown and described what are believed to be the preferred embodiments of my invention, it is nevertheless to be understood that minor changes may be made in the form, combination and arrangement of parts without departing from the spirit and scope of my invention as claimed. 55

What I claim as new is:—

A device of the class described comprising a tubular handle, a pair of jaws secured to one end thereof, one of said jaws including a tubular socket member for receiving 60 said handle with the jaw carried thereby being immovable relative thereto, the other of said jaws being pivoted to the rigidly mounted jaw, an angularly disposed arm extending from the inner end of said pivoted jaw, 65 the tubular handle and socket member having registering openings therein, an operating lever at the opposite end of said handle, flexible connections between said operating lever and said jaw arm extending through 70 said tubular handle and registering openings.

In testimony whereof I affix my signature.

STANISLAW OBOLEWICZ.
